UNITED STATES PATENT OFFICE.

A DOLF SENGEL, OF DARMSTADT, GERMANY.

CONTINUOUS-CURRENT SHUNT-MACHINE.

SPECIFICATION forming part of Letters Patent No. 624,986, dated May 16, 1899.

Application filed November 11, 1898. Serial No. 696,129. (No model.)

To all whom it may concern:

Be it known that I, ADOLF SENGEL, professor at the Electrotechnical Institute at Darmstadt, in the Grand Duchy of Hesse, Germany, have invented new and useful Improvements in Continuous-Current Shunt-Machines, of which the following is a specification.

As is well known, the construction of the magnet-winding in continuous-current shunt-machines for high potentials involves great difficulties, because with an increasing potential the cross-section of the shunt-wire employed diminishes with the increasing number of windings, so that on one hand there is an increase in the cost of material and manufacture, while on the other hand there is an increased risk of striking through the magnet-winding in case of careless throwing of the shunt-circuit current out of circuit. The two first-mentioned drawbacks are especially noticeable in small machines. Resistances might be employed to diminish the potential at the terminals of the shunt-circuit to any desired extent; but this would entail a permanent loss of energy in the resistance, and the saving in the manufacture of the magnet-winding would be more or less offset by the increased cost of the resistance.

The construction hereinafter described permits exciting the magnets in a shunt-machine without any loss and with only half the potential at the brushes.

Figure 1 illustrates an arrangement of connections of this kind embodying my invention, and Fig. 2 illustrates such an arrangement in combination with a starting resistance.

In the drawings, A indicates the armature of a continuous-current machine.

C indicates the current-delivery device or commutator, with the two collecting-brushes B and B'. Mounted on the shaft is an insulated collector-ring S, which is conductively connected with any suitable point of the armature-winding—for example, by means of the current-collector or commutator-segment s—and upon which there rubs a third brush B''. When the machine is set in operation and is normally excited, there is produced between the brushes B and B', as is well known, a constant potential—that is to say, a potential

which has at every moment the same direction and the same value. Now the potential which exists between the brush B'', rubbing 55 on the contact-ring S, and one of the brushes B or B', although having the same direction, is continually varying in amount according to the position of the segment s, that is connected with the rubbing-ring S, in relation 60 to the brush B or B'.

On considering, for example, the course of the potential between B'' and B it will be seen that the potential between the two brushes is equal to zero when the segment s comes under the brush B. The potential reaches its maximum when the segment s after half a revolution comes in contact with the brush B, and it is in this case equal to the potential at the terminals of the machines B B'. In the 70 other positions the potential B'' B has a value which is between the maximum and zero. Consequently the potential is a pulsatory one. This pulsatory potential may be conceived to be produced by the combination of a pure continuous-current and of an alternating-current potential, which are of such amounts that both the continuous-current potential and also the amplitude of the alternating-current potential become equal to half the potential at 75 the terminals. If an inductionless resistance be included between B and B'', a current which will also continually vary between zero and a maximum will be produced in this resistance, and this current can also be split up 80 into a pure continuous current and an alternating current. Both currents are of an amount such as if a continuous-current potential of half the potential of the machine and an alternating-current potential having an amplitude also equal in value to half the potential of the machine were to act simultaneously 85 at the terminals of the resistance. If now the resistance which is inserted between B'' and B has self-induction, the latter will not affect 90 the continuous current in any way, but will tend to weaken the alternating current, and in a higher degree the greater the coefficient 95 of the self-induction and the higher the periodic number or frequency of the alternating current, so that with self-induction and a periodic number of any reasonably high value 100 the current which is produced can be practically considered to be a continuous current

having a potential equal to half the potential at the brushes. Now the shunt-windings of dynamo-machines have an extremely high self-induction. If, therefore, the ends 5 of the shunt-winding be placed, as shown in Fig. 1, between the brushes B and B'', with the inclusion of a regulating resistance R, then even with a low periodic number the current strength produced in the shunt-current circuit will reach exactly the same value 10 as if this circuit were fed with half the brush-potential B B''. In the same manner this arrangement of connections may be employed in shunt-circuit motors. Fig. 2 shows an arrangement of this kind in combination with a starting resistance W. The other reference-letters are the same as those employed in Fig. 1. The connections of the armature are made in the usual manner. One end of the 15 shunt-circuit winding is connected through the contact-bar k with one pole of the lead, while the other end is connected to the brush B''. The use of this arrangement of connections in motors has further the advantage 20 that so long as the armature is at rest the full working potential will act at the terminals of the shunt-circuit, and therefore the exciting current will be twice as great as in normal working and the attractive force will be con- 25 siderably higher than when the ordinary arrangement of connections is used. With increasing speed of the armature the potential 30 at the terminals of the shunt-circuit will di-

minish and will reach its normal amount, which is equal to half the potential in the 35 lead when the whole of the resistance in the armature-current circuit has been cut out.

The rubbing-ring S may be dispensed with when the armature-winding is connected at one point with the iron body, and in this manner with the shaft and with the magnet-frame, and the one end of the shunt-circuit winding is connected to the frame instead of to the brush B''. This does not make any alteration 40 with reference to the mode of operation 45 of the entire arrangement.

Now what I claim, and desire to secure by Letters Patent, is the following:

1. In a shunt-dynamo or shunt-motor the connection of one end of the shunt with a 50 point of the main line and the other end of the shunt with a fixed point of the armature-winding, substantially as described.

2. In a shunt-dynamo or shunt-motor the connection of one end of the shunt with a delivery-brush of the main line and the other end of the shunt with a rubbing-ring placed 55 in the winding of the armature at a fixed point thereof substantially as described.

In testimony whereof I have signed my 60 name to this specification in the presence of two subscribing witnesses.

ADOLF SENGEL.
